CLAIM

The ornamental design for a handle for faucet, as shown and described.

DESCRIPTION

FIG. 1 is a plan view of the bottom of the faucet showing my new handle design with bottom surfaces of flat planar configuration;

FIG. 2 is an elevational view of the rear thereof;

FIG. 3 is an elevational view of one side thereof;

FIG. 4 is an elevational view of the front thereof;

FIG. 5 is a plan view of the top thereof; and,

FIG. 6 is a perspective view of the spout and handles thereof. The spout of the faucet shown in broken lines in the drawings forms no part of the present design.
